[57] CLAIM

The ornamental design for a folding sanitary care unit, as shown and described.

DESCRIPTION

FIG. 1 is a left front perspective view of a folding sanitary care unit showing my new design, with the unit shown in its extended condition;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof;

FIG. 7 is a bottom plan view thereof;

FIG. 8 is a left front perspective view thereof, with the unit in its folded condition; and

FIG. 9 is a right side elevation view of FIG. 8.
